MANUFACTURE OF GASOLINE AND FUEL OIL

Filed June 15, 1937

UNITED STATES PATENT OFFICE

2,170,795

MANUFACTURE OF GASOLINE AND FUEL OIL

John Joseph Downey, Los Angeles, and William Wallace Murray, Downey, Calif., assignors to Sinclair Refining Company, New York, N. Y., a corporation of Maine

Application June 15, 1937, Serial No. 148,272

8 Claims. (Cl. 196—48)

In the processing of crude petroleum stocks to produce lubricating oils, the requirements of the lubricating oil products govern the processing for the simple reason that the lubricating oil products 5 are more valuable than other products produced as a result of such processing. When crude petroleum stocks not useful or not required for the production of lubricating oils are processed for the production of motor fuel gasoline, residual 10 values are recovered either as coke or, more commonly, as fuel oil. Gasoline being more valuable than fuel oil, such processing has for the most part been governed by the requirements of gasoline production. When such processing, as applied 15 to the particular crude petroleum stocks to be processed, has converted such stocks predominantly into gasoline, such determination of the conditions of processing has not generally been economically satisfactory. However, as applied 20 to crude petroleum stocks of a character such that the value of the fuel oil product, the principal product other than gasoline, becomes substantial with respect to the value of the gasoline product, such determination of the conditions of processing 25 is not economically satisfactory. Specifically, if the value of the fuel oil product is unimportant with respect to the value of the gasoline product in any particular instance, the quality of the fuel oil product is of correspondingly minor im- 30 portance, but if the proportion of fuel oil produced is so large with respect to the proportion of gasoline produced that the value of the fuel oil product becomes important with respect to the value of the gasoline produced, notwithstanding 35 the greater value of gasoline as compared to fuel oil per unit quantity, then the quality of the fuel oil product, through its effect upon the value of the total production of fuel oil may, and frequently does, limit the economic value of the over-all 40 processing or even render the over-all processing uneconomic. The processing of the more generally available California crude petroleums and reduced crude petroleums, from which lower boiling fractions have been separated by distillation, 45 for the production of gasoline and fuel oil illustrates the situation in which the quality of the fuel oil is a major factor in determining the economic merit of the over-all processing. Any decrease in the ratio of available crude petroleum 50 stocks to gasoline requirements tends to increase the significance of this factor.

This invention relates to improvements in the manufacture of gasoline and fuel oil from crude petroleum stocks, either not useful or not required 55 for the production of lubricating oils, and more

particularly from asphaltic petroleum stocks containing a high boiling wax bearing fraction such as those generally occurring in California.

Motor fuel gasoline must meet definite and established requirements as to volatility and 5 should have good anti-knock value. Several methods of processing crude petroleum stocks to convert substantial portions of them into motor fuel gasoline, by cracking, have been devised and a number of them have been brought to a high 10 state of efficiency with respect to the production of gasoline. Fuel oil must remain fluid and must be sufficiently fluid to permit handling under the conditions prevailing, or which normally might be encountered, in connection with the use for 15 which it is intended and, for most purposes, it must be so free from sediment that it will not tend, in any serious measure, to choke or plug lines, valves, pumps, and burners, and the parts through which it must flow from storage re- 20 ceptacles. In fuel oil specifications, these requirements, appear as a maximum viscosity limitation, as a maximum sediment content, and as a maximum pour, a maximum temperature below which the oil ceases to flow freely. 25

Fuel oil specifications also commonly include a minimum gravity, that is a maximum specific weight, limitation although this limitation is more an arbitrary reflection of the experience of the fuel oil users with respect to other qualities than 30 any fundamental quality to which it directly relates. In the processing of California crude petroleum stocks for the production of gasoline and fuel oil, for example, it is generally assumed that a satisfactory fuel oil should have a gravity of 10° 35 A. P. I. as a minimum. This assumption apparently is based upon observation that the methods of processing hitherto generally used produced fuel oils which were too dirty, that is which contained too much sediment, if carried far enough 40 to produce a heavier product.

Residual stocks produced from crude petroleum stocks tend to have a viscosity and a pour too high to be satisfactory as fuel oil. Decomposition at elevated temperatures, and usually 45 under pressure, will reduce the viscosity and the pour of such stocks, but as ordinarily practiced such decomposition, sometimes called "viscosity breaking", tends to increase the sediment content of the residual stock, and this tendency increases as the severity of the decomposition necessary to effect the required reduction in viscosity or pour increases. Or, the viscosity and the pour of such stocks may be reduced by leaving in the residual stock, or by blending with it, dis- 55

tillate stocks such as gas oil, but such gas oil stocks are usually more valuable than the residual stock, particularly as raw material for the production of gasoline by cracking. As a consequence the refiner of such crude petroleum stocks has as alternatives the production of a satisfactory fuel oil including fractions potentially more valuable for gasoline production and processing to secure a maximum recovery of gasoline with accompanying production of low quality and consequently low value if not unmerchantable fuel oil. Neither alternative meets the economic requirements of such a refiner and, as the ratio between available crude petroleum stocks and gasoline requirements diminishes, the refiner in this position is subjected to increasing economic difficulties.

This invention enables the refiner processing crude petroleum stocks to produce gasoline and fuel oil to increase the recovery of gasoline without prejudice to the quality of the residual fuel oil produced, or conversely to improve the quality of the fuel oil produced without prejudice to gasoline recovery, and this is one of the more important advantages of the invention. This advantage is, moreover, obtained without sacrifice of efficiency or economy, but actually with improvements in both efficiency and economy in several respects.

30 This invention provides a combined operation in which gasoline is produced in a cracking step to which only clean distillate oil is supplied and in which conditions appropriate to avoid carbon formation are maintained, in which decomposition of residual stocks appropriate to produce fuel oil at required viscosity and pour is effected without carbon formation by heat exchange with the hot oil products from the cracking step for a controlled period, in which a maximum of clean 35 distillate stock to be supplied to the cracking step is separated from this residual stock following this controlled decomposition under conditions avoiding further decomposition, and in which stocks relatively more valuable for cracking 40 to produce gasoline are separated from stocks relatively more valuable for blending with residual stocks to produce fuel oil, these separated stocks then being used each for the purpose to which it is best adapted. The invention comprises the combined operation and improvements 45 in various steps of the combined operation and improvements in the adaptation of the combined operation to particular residual stocks presenting specific processing problems.

50 In one form of operation embodying this invention, a stream of distillate oil is heated to a high cracking temperature under superatmospheric pressure, the hot oil products of this heating and the residual stock to be processed are 55 introduced into a vapor separating receptacle in which they are in direct heat exchanging relationship, a vapor mixture, including the gasoline product and gas oil, and a residual stock mixture are taken off from this vapor separating 60 receptacle, a high boiling gas oil is vaporized from this residual stock mixture by its contained heat in an evaporator maintained under a pressure lower than that maintained in the vapor separating receptacle, this gas oil, as a vapor 65 mixture, and a reduced residual stock mixture are taken off from this evaporator, the vapor mixture taken off from the vapor separating receptacle is fractionated to form a gasoline fraction, a high boiling gas oil and a separate lower 70 boiling gas oil, the high boiling gas oil from this

fractionation and that taken off from the evaporator are combined and supplied to the heating first-mentioned, and the lower boiling gas oil from this fractionation is blended with the reduced residual stock from the evaporator to form 5 fuel oil.

The accompanying drawing illustrates diagrammatically, generally in elevation one form of apparatus adapted for practicing this invention. In the apparatus illustrated in the drawing, the form of operation just described is carried out as follows: A stream of distillate oil, supplied through connection 41, forced through the heater 1 by means of pump 7 and discharged through connection 19, is heated in the heater 1 to a cracking temperature upwards of 900° F. under a pressure of from 300 to 800 pounds per square inch gauge, as discharged, for example. After passing through the pressure regulating and reducing valve 21, the hot oil products discharged from the heater 1 enter the lower part of the vapor separating receptacle 2 into the upper part of which the crude petroleum stock to be processed is introduced through connection 22 by means of pump 8. A vapor mixture including gasoline and gas oil is taken off from the upper end of the vapor separating receptacle 2 through connection 23 and introduced into the lower part of the fractionating tower 4, and the residual stock mixture separated in the vapor 30 separating receptacle 2, including residual components of the hot oil products discharged from the heater as well as residual components of the stock introduced through connection 22, is discharged through the pressure regulating and reducing valve 25 and connection 24 into the evaporator 3. A pressure of from 20 to 60 pounds per square inch for example, may be maintained in the vapor separating receptacle 2. A vacuum of from 10 to 25 inches of mercury, for example, 40 may be maintained in the evaporator 3, by means of the exhauster 31 operating in conjunction with pumps 11 and 12. A high boiling gas oil is vaporized in the evaporator 3 and, passing to the heat exchangers 32 and 33 through connection 34, is condensed, the condensate being collected in receiver 35. Except for that part introduced into the upper end of the evaporator 3 through connection 36 by means of pump 12, this condensed high boiling gas oil is introduced 50 into the lower part of the fractionating tower 4 through connection 42 by means of pump 12. The fractionating tower 4 separates the stocks introduced through connections 23 and 42 into a gasoline fraction discharged through connection 55 43, a high boiling gas oil supplied to the heater 1 through connection 41 and a low boiling gas oil taken off as a side stream through the stripper 48 and connection 45. Except for that part returned to the fractionating tower 4 through 60 the absorber 5, this lower boiling gas oil is discharged through connection 46. The reduced residual stock mixture separated in the evaporator 3 is discharged through connection 37 by means of pump 11. The gasoline product is separated from the vapor mixture discharged from the fractionating tower 4 through connections 43 and 38, in any convenient manner, such as by the processing subsequently described. The fuel oil product is produced by blending the reduced residual stock discharged through connection 37 and the lower boiling gas oil discharged through connection 46.

The heating, in which the stream of distillate oil is heated to a high cracking temperature un- 75

der superatmospheric pressure, the heating carried out in the heater 1 in the apparatus illustrated, for example, is, in the combined operation of this invention so controlled with respect to temperature, temperature gradient, pressure and time as to prevent substantial formation of carbon or sediment, during this step of the operation. The correlation of these several factors to this end and various forms of heating apparatus for maintaining such correlation, as applied to the processing of a clean distillate stock, are well known. The particular form of apparatus and the particular technique may be chosen in any particular instance, to meet the requirements of the particular refiner. In general, however, it is advantageous, in the combined operation of this invention, to avoid substantial digestion, or "soaking," of the hot oil products flowing through and discharged from this heating step prior to introduction into the vapor separating receptacle. That is, in the combined operation of the invention it is advantageous to have the temperature of the oil progressively increased as it flows through the heating step and to avoid conditions which tend to maintain the flowing oil prior to discharge into the vapor separating receptacle at approximately the same temperature for any prolonged period of time. Such digestion tends to increase the sediment content of the fuel oil produced by the combined operation. The conditions in the vapor separating receptacle are so controlled that no substantial carbon formation takes place therein. A temperature, and a pressure, sufficient to effect a reduction of the viscosity of residual components of the introduced residual stock while passing therethrough may, however, be maintained therein with advantage. For example, a maximum temperature approximating 820°-840° F., and the corresponding pressure may be maintained in this externally unheated vapor separating receptacle while maintaining therein a liquid body equivalent in volume to about 8-10 minutes discharge of residual stock mixture therefrom. The conditions in the evaporator, into which the residual stock mixture separated in the vapor separating receptacle is discharged, are so controlled that no substantial decomposition takes place therein.

50 As applied to an asphaltic petroleum stock containing a high boiling wax bearing fraction, a California crude petroleum or reduced crude petroleum of this character for example, the high boiling wax bearing fraction of the crude petroleum stock is taken off from the vapor separating receptacle into which this crude petroleum stock is introduced as a component of the residual stock mixture separated in the vapor separating receptacle and is then vaporized from this residual stock mixture without substantial decomposition in the evaporator. In the vapor separating receptacle, conditions of temperature and pressure appropriate to effect a reduction of the viscosity of residual components of the introduced crude petroleum stock but without substantial formation of carbon or sediment, are with advantage maintained. Then, in the evaporator, further decomposition which would tend to increase the sediment content of the reduced residual stock is avoided by effecting this step of the operation under a lower pressure and under a correspondingly lower temperature and by effecting this vaporization by the contained heat of the oil, through this pressure reduction, rather than by the application of external heat to the

evaporator. A reduction of the pour of the reduced residual stock is effected by the separation, in the evaporator, of the high boiling wax bearing fraction. The high boiling wax bearing fraction separated in the evaporator, a high boiling gas oil, is then condensed and supplied, as a clean distillate oil, to the heating in which it is cracked for the production of gasoline. The clean distillate oil supplied to the cracking for the production of gasoline also comprises, with advantage, the high boiling gas oil condensed from the vapor mixture taken off from the vapor separating receptacle. This vapor mixture taken off from the vapor separating receptacle is, with advantage, fractionated to form a gasoline fraction, a high boiling gas oil and a separate lower boiling gas oil. Such high boiling gas oil is a desirable stock, or stock component, for cracking to produce gasoline. Such lower boiling gas oil is less desirable as a stock for cracking to produce gasoline, being relatively refractory and tending to reduce the capacity of the cracking step if supplied thereto in admixture with the higher boiling gas oils taken off from the vapor separating receptacle and the evaporator, but it is substantially free from wax and is very effective, as a diluent, in reducing the viscosity of residual stocks with which it is blended and is, with advantage, blended with the reduced residual stock separated in the evaporator to produce fuel oil of improved viscosity and pour.

The invention will be further illustrated by the following specific example of one operation embodying the invention as practiced in apparatus of form illustrated in the accompanying drawing: A stream of clean distillate oil is forced through the heater 1 by means of pump 7 at a rate of about 12,050 gallons per hour and at a temperature, entering the heater, of about 610° F., and in the heater it is progressively heated to a temperature of about 940° F. under a pressure, as discharged from the heater, approximating 400 pounds per square inch. The heater may consist, for example, of two banks of tubes 3" in inside diameter, 74 tubes exposed over 32 feet of their length being serially connected in each bank and the two banks being connected in parallel. The pressure on the stream of hot oil products discharged from the heater is reduced to about 55-60 pounds per square inch as it passes through the valve 21 through which it enters the vapor separating receptacle 2. In addition to the hot oil products discharged into the vapor separating receptacle 2 from the cracking heater 1, reduced California crude petroleum is introduced into the vapor separating receptacle 2 through connection 22 by means of pump 8 at a rate of about 4,830 gallons per hour and at a temperature, entering the vapor separating receptacle, approximating 415° F. After leaving the pump 8, the reduced crude petroleum flows first through the heat exchanger 32 and then through the heat exchanger 40, being thus pre-heated to this temperature. Temperatures of about 735° F. and 825° F. are maintained in the upper and lower ends respectively, of the vapor separating receptacle 2. A vapor mixture is taken off from the vapor separating receptacle through connection 23, through which it is discharged into the fractionating tower 4, at a rate of about 13,- 035 gallons per hour and a reduced residual stock is discharged from vapor separating receptacle 2 through connection 24 at a rate of about 3,995 gallons per hour. A volume of liquid residue approximating 570 gallons is maintained in the low-

er end of the vapor separating receptacle. A subatmospheric pressure corresponding to about 14" of mercury is maintained in the receiver 35 by means of the exhaustor 31. This receiver 5 is in free communication with the evaporator 3 through connection 34 and a corresponding subatmospheric pressure is thus maintained in the evaporator. The pressure on the residual stock discharged from the vapor separating receptacle 2 is reduced as it passes through valve 25 to enter the evaporator. Under these conditions, the contained heat of the residual stock mixture discharged from the vapor separating receptacle at a temperature approximating 825° F. is sufficient 10 to maintain, in conjunction with the refluxing subsequently described, temperatures of about 710° F. and 730° F. in the upper and lower ends respectively, of the evaporator 3. The reduced 15 residual stock mixture, tar, is pumped, by means of pump 11, from the lower end of the evaporator 20 at a rate of about 2,470 gallons per hour. The vapor mixture separated in the evaporator 3 is taken off through connection 34 at a rate of about 1,525 gallons per hour, this vapor mixture being 25 condensed and cooled to a temperature of 220° F. as it passes through the heat exchangers 32 and 33. About 155 gallons per hour of this condensate is reintroduced into the evaporator through connection 36 and the balance, about 30 1,370 gallons per hour, is pumped into the fractionating tower 4 through connection 42 by means of pump 12. The fractionating tower 4 is maintained under a pressure of about 30-40 pounds per square inch and temperatures of about 365°-370° F. and 625° F. are maintained at the upper 35 and lower ends respectively, of this fractionating tower by appropriate refluxing. The gasoline fraction including the gas produced in the operation is discharged from the fractionating tower 40 4 through connection 43 at a rate of about 5,650 gallons per hour. A lower boiling gas oil, an intermediate fraction, is taken off from the fractionating tower 4 as a side stream through the stripper 44 and a high boiling gas oil is collected 45 in the lower end of the fractionating tower 4. Stocks subjected to fractionation in the fractionating tower 4 include the several stocks or stock mixtures introduced through connection 42 as well as the stock introduced as a vapor mixture 50 through connection 23. Appropriate refluxing is effected by condensing a part of the vapor mixture discharged from the fractionating tower through connection 43, in condenser 39 discharging into receiver 47, and reintroducing this condensate 55 into the upper end of the fractionating tower through connection 48 by means of pump 15 at a rate of about 2,960 gallons per hour and at a temperature approximating 85°-90° F. Refluxing by circulation of any appropriate cooling 60 medium through the heat exchanger 49 may be used in place of or as a supplement to such refluxing by reintroduction of a condensed portion of the discharged vapor mixture. A part of the lower boiling gas oil taken off through the stripper 65 per 44 is circulated through the absorber 5 and back to the fractionating tower 4, through connection 42 by means of pump 17. This part of the lower boiling gas oil is used as an absorbent in the absorber 5 to recover gasoline constituents 70 from the gas mixture separated from the gasoline condensate in receivers 47 and 51, the absorbed gasoline constituents being vaporized from the absorber upon reintroduction of the absorbent into the fractionating tower 4. The balance of 75 the lower boiling gas oil taken off through the

stripper 44, about 830 gallons per hour, is discharged through connection 46. A part, about 8,590 gallons per hour, of the high boiling gas oil accumulating in the lower end of the fractionating tower 4 at a temperature approximating 625° F. is used as a heating medium in the operation of the stabilizer 6 and in preheating in heat exchanger 60 the reduced crude petroleum to be introduced into the vapor separating receptacle 2. That part of this high boiling gas oil used in the 10 operation of the stabilizer, about 1,310 gallons per hour, is circulated through the heat exchanger or reboiler 61 by means of pump 13 and that part used in preheating the reduced crude petroleum is circulated through the heat exchanger 60 by 15 means of this same pump 13, the oil returning from the heat exchangers 60 and 61 being reintroduced into the fractionating tower 4 through connection 42. In addition to the high boiling gas oil from the receiver 35, the low boiling gas 20 oil charged with absorbed gasoline constituents from the absorber 5 and the circulated gas oil returned from heat exchangers 60 and 61, virgin gas oil of a gravity approximating 33.5°-34° A. P. I. is pumped into the fractionating tower 25 4 through connection 42 by means of pump 9 at a rate of about 950 gallons per hour. The clean distillate stock supplied to the cracking heater 1 is the composite high boiling gas oil character stock separated in the lower end of the fractionating tower 4 and is supplied to the pump 7 delivering to the cracking heater 1 through connection 41. That part of the vapor mixture discharged from the fractionating tower 4 through connection 43 not delivered to the condenser 39 30 is delivered to the condenser 50 discharging into the receiver 51. The bulk of the gasoline content of this part of the vapor mixture is condensed in the condenser 50 and is separated from 35 gases and uncondensed vapors in the receiver 51. The mixture of gases and uncondensed vapors separated in the receivers 47 and 51 is discharged 40 into the absorber 5 through connection 52 for recovery of gasoline constituents as previously described. The absorbent oil supplied to the absorber 5 is cooled, in the heat exchanger 53, to a temperature of about 80° F. before being introduced into the upper end of the absorber through connection 54. A pressure of about 30 pounds per square inch is maintained in the receiver 51, 45 and in the receiver 47, to promote the separation of condensable constituents from the gas mixture in these receivers. A pressure of about 28 pounds per square inch is maintained in the absorber 5. The gasoline condensate separated in the receiver 51 is pumped, by means of pump 16, through connections 62 and 63 and heat exchanger 64 into the stabilizer 6 in which this gasoline condensate is accurately fractionated at the lower 50 end of its boiling range to produce a gasoline product discharged from the lower end of the stabilizer 6 through heat exchanger 66, cooler 65 and connection 66 at a rate of about 2,120 gallons per hour. Stabilizer 6 is operated under a pressure, at the upper end, of about 250-260 pounds 55 per square inch. A temperature of about 380°-385° F. is maintained at the lower end of stabilizer 6 by means of heat supplied through heat exchanger 61. A temperature of about 105° F. is maintained at the upper end of stabilizer 6 by 60 reintroducing condensate condensed and separated from the gas mixture escaping from the upper end of the stabilizer through connection 67, in condenser 68 and receiver 69, through connection 70 by means of pump 18. Dry gas is 65

5 discharged from the upper end of the absorber 5 through connection 55 at a rate of about 31,600 cubic feet per hour and dry gas is discharged from receiver 69 through connection 71 at rate 5 of about 1,500 cubic feet per hour.

In one operation conducted as just described, in apparatus of the form illustrated in the accompanying drawing, supplying California reduced crude petroleum having a gravity of 17.3° 10 A. P. I. and virgin gas oil from California crude petroleum having a gravity of 33.8° A. P. I., a tar separated as a reduced residual stock in the evaporator 3 having a gravity of 4.9° A. P. I., a low boiling gas oil having a gravity of 26.9° A. P. I. and 15 163 seconds, a pour of 100° F. and a content of sediment by extraction with benzol of 0.06%. The low boiling gas oil produced was available for 20 blending with this tar in proportions exceeding 20% of the blended fuel oil product. In blends 25 comprising 10% and 20% of such gas oil, the Furol viscosities at 210° F. of the blends were 46 seconds and 22 seconds respectively, the pours of the blends were 75° F. and 40° F. respectively, and the sediment contents by extraction with 30 benzol were 0.04% and 0.03% respectively.

The combined operation, as carried out in apparatus of the form illustrated in the accompanying drawing, is conveniently controlled by reference to the heat balance in the vapor separating receptacle. With hot oil products discharged from the cracking heater into the vapor separating receptacle at a given rate and at a given temperature, the rate at which a residual stock can be introduced into the vapor separating 40 receptacle is governed by the temperature at which this residual stock is introduced, the permissible rate of introduction of the residual stock increasing and decreasing respectively, with increase or decrease of the temperature at which 45 the residual stock enters the vapor separating receptacle. If this relationship is adjusted to permit the introduction of the residual stock at a rate sufficient to produce the total clean distillate oil, including the high boiling gas oil taken off 50 from the vapor separating receptacle and the high boiling gas oil taken off from the evaporator, required to supply the cracking heater, additional stock need not be supplied to meet the requirements of the heater. However, the temperature at which the residual stock is introduced into the vapor separating receptacle must 55 also be so related to the rate at which it is introduced into the vapor separating receptacle, and with respect to the rate at which heat is supplied to the vapor separating receptacle in the hot oil products discharged from the cracking heater, that conditions, and particularly the temperature, in the vapor separating receptacle, do not reach a point at which decomposition involving 60 the formation of carbon or an increase in the sediment content of the residual stock mixture separated therein becomes substantial. In general, this means that the temperature of the residual stock as introduced into the vapor separating 65 receptacle must not be too high. An operating balance will be found, in any particular instance, between the limits fixed by these two requirements, namely, the avoidance of objectionable decomposition in the vapor separating receptacle and the production of sufficient clean 70

distillate oil to supply the cracking heater, any variation being made up by a supplementary supply of a clean distillate oil from some external source. The particular method used for preheating the crude petroleum stock introduced into the vapor separating receptacle is not essential to this invention. If it be fire-heated, however, it must not be so heated to a temperature at which objectionable decomposition begins. In the apparatus illustrated in the accompanying drawing, for example, after leaving the pump 8, the crude petroleum stock may flow in whole or in part through the heat exchanger 32 and in whole or in part through the heat exchanger 40, the several valves 81, 82, 83, 84, 85, 86 and 87 being provided for distribution and regulation 15 of this flow.

Several advantages of the invention will be apparent from the foregoing. In the combined operation of the invention the cracking to produce gasoline is separated from the decomposition to reduce the viscosity, and pour, of the fuel oil in respects which permit effective cracking of an increased proportion of the stock supplied to the combined operation after separation as a 20 clean distillate oil while avoiding over-decomposition alike of the clean distillate oil and the separated residual components tending to produce dirty fuel oil although this cracking and decomposition are combined in respects which 25 utilize the heat content of the hot oil products discharged from the cracking operation to effect the decomposition of the residual components of the stock supplied to the combined operation in a particularly advantageous manner and which 30 enable the residual components produced by the cracking of the clean distillate oil to be used with maximum effect in reducing the viscosity, and pour, of the composite residual stock mixture produced by the operation, without contamination of the residual stock mixture with carbon or sediment. The residual components of the stock supplied to the combined operation are subjected to decomposition under mild conditions and increased proportion of the stock supplied 35 to the combined operation is separated as a clean 40 distillate oil and as such is subjected to effective cracking to produce gasoline, thus permitting a more effective cracking to produce gasoline of an increased proportion of the total stock supplied 45 to the combined operation without involving over-cracking or over-decomposition of any part of the total stock. Also, the higher boiling gas oil separated in the fractionating step of the 50 combined operation of the invention is more desirable 55 as a stock for cracking to produce gasoline than the lower boiling gas oil separated in this fractionation and in the combined operation this more desirable cracking stock is subjected to effective cracking while the lower boiling gas oil, 60 relatively refractory and less desirable as a cracking stock but more effective as a diluent for blending with the reduced residual stock mixture separated in the evaporator for the production of fuel oil is made available for such blending. 65

The term "cracking" is used herein to refer to pyrolysis to produce gasoline as distinguished from pyrolysis limited in effect to the reduction of viscosity, or pour, and not with that broader meaning with which it is sometimes used to include pyrolysis generally. In referring to a "high cracking temperature" herein reference is intended to cracking temperatures ranging upwards from 900° F. to about 975° F.-985° F., for example. The term "carbon" is used herein to 70 75

include those solid or semi-solid materials, carbon-like or coke-like, which are produced by pyrolysis and is not intended to be limited to carbon in the strict chemical sense. Reference 5 to "wax bearing" stocks herein is not intended as a reference to stocks necessarily obtaining any large proportion of wax. The presence of determinable quantities of wax, by low temperature extraction with ether and absolute alcohol 10 of the distillate obtained on running a sample to coke, even though in but fractions of a per cent, in crude petroleum stocks tends to involve difficulties of the sort with which this invention deals. The term "crude petroleum stocks" is intended 15 to include both crude petroleum as such and reduced crude petroleum. "Over-cracking" or "over-decomposition" as those terms are used herein can be recognized by extraction with benzol of the residual product of the cracking or decomposition, objectionable over-cracking or over-decomposition usually being indicated by a sediment content on such extraction with benzol of as much as one tenth of one per cent or more.

The unusual cleanliness of the tar recovered as 20 a reduced residual stock mixture from the evaporator in combined operation of this invention makes it available not only for the production of fuel oil but also for the production of road oil and, with appropriate blowing, of asphalt. 25 Such reduced residual stocks can be regularly produced by the combined operation of this invention, with sediment contents, by extraction with carbon bisulphide and carbon tetrachloride, of substantially less than one tenth or two tenths 30 of one per cent. It is thus possible, by separating sufficient distillable material from the reduced residual stock mixture in the evaporator to produce merchantable road oil as a direct product of the combined operation. The same properties 35 which make this reduced residual stock mixture desirable as road oil also make it desirable as a stock to be processed for the production of asphalt.

We claim:

45 1. In the manufacture of gasoline and fuel oil from asphaltic petroleum stocks containing a high boiling wax bearing fraction of the type generally occurring in California, the improvement which comprises heating a stream of distillate oil 50 to a high cracking temperature under super-atmospheric pressure and controlling the temperature, temperature gradient, pressure and time during said heating to prevent substantial formation of carbon therein, reducing the pressure on 55 the hot oil products of said heating and bringing them into direct heat exchanging relationship with the asphaltic stock containing the high boiling wax bearing fraction in a vapor separating receptacle without prior heating of said asphaltic 60 stock to a temperature at which substantial decomposition occurs, taking off from said receptacle a residual stock mixture including the high boiling wax bearing fraction and a vapor mixture including gas oil and gasoline; vaporizing the high boiling wax bearing fraction from this 65 residual stock mixture without substantial decomposition by the contained heat of the oil in an evaporator maintained under a pressure lower than that maintained in said receptacle, and condensing this high boiling wax bearing fraction and supplying it to said heating.

70 2. In the manufacture of gasoline and fuel oil from asphaltic petroleum stocks containing a high boiling wax bearing fraction of the type generally occurring in California, the improvement 75

which comprises heating a stream of distillate oil to a high cracking temperature under super-atmospheric pressure and controlling the temperature, temperature gradient, pressure and time during said heating to prevent substantial formation of carbon therein, reducing the pressure on the hot oil products of said heating and bringing them into direct heat exchanging relationship with the asphaltic stock containing the high boiling wax bearing fraction in a vapor separating receptacle without prior heating of said asphaltic stock to a temperature at which substantial decomposition occurs, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, and condensing this high boiling wax bearing fraction and supplying it to said heating, together with gas oil condensed from said vapor mixture.

75 3. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure and controlling the temperature, temperature gradient, pressure and time during said heating to prevent substantial formation of carbon therein, bringing the hot oil products of said heating into direct heat exchanging relationship with the asphaltic stock containing the high boiling wax bearing fraction in a vapor separating receptacle without prior heating of said asphaltic stock to a temperature at which substantial decomposition occurs, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, condensing this high boiling wax bearing fraction to form a high boiling gas oil, fractionating said vapor mixture to form a gasoline fraction, a high boiling gas oil, and a separate lower boiling gas oil, and combining and supplying to said heating said high boiling gas oils.

4. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure and controlling the temperature, temperature gradient, pressure and time during said heating to prevent substantial formation of carbon therein, bringing the hot oil products of said heating into direct heat exchanging relationship with the asphaltic stock containing the high boiling wax bearing fraction in a vapor separating receptacle without prior heating of said asphaltic stock to a temperature at which substantial decomposition occurs, taking off from said receptacle a residual stock mixture including the high boiling wax bearing fraction and a vapor mixture including gas oil and gasoline, vaporizing the high boiling wax bearing fraction

from this residual stock mixture without substantial decomposition by the contained heat of the oil in an evaporator maintained under a pressure lower than that maintained in said receptacle, condensing this high boiling wax bearing fraction to form a high boiling gas oil, fractionating said vapor mixture to form a gasoline fraction, a high boiling gas oil, and a separate lower boiling gas oil, and combining and supplying to said heating said high boiling gas oils, and blending said lower boiling gas oil with residual stock from said evaporator to form fuel oil.

5. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure without substantial digestion, bringing the hot oil products of said heating into direct heat exchanging relationship with the asphaltic stock containing the high boiling wax bearing fraction in a vapor separating receptacle without prior heating of said asphaltic stock to a temperature at which substantial decomposition occurs, maintaining a temperature and pressure in said vapor separating receptacle sufficient to effect a reduction of the viscosity of residual components of said asphaltic stock but 30 without substantial formation of carbon therein, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, and condensing this 40 high boiling wax bearing fraction and supplying it to said heating.

6. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure without substantial digestion, bringing the hot oil products of said heating into direct heat exchanging relationship with the asphaltic stock containing the high boiling wax bearing fraction in a vapor separating receptacle without prior heating of said asphaltic stock to a temperature at which substantial decomposition occurs, maintaining a temperature and pressure in said vapor separating receptacle sufficient to effect a reduction of the viscosity of residual components of said asphaltic stock but without substantial formation of carbon therein, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, and condensing this high boiling wax bearing fraction and supplying it to said heating, 70 together with gas oil condensed from said vapor mixture.

7. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure and controlling the temperature, temperature gradient, pressure and time during said heating to prevent substantial formation of carbon therein, introducing the hot oil products of said heating into an externally unheated vapor separating receptacle and therein bringing said hot oil products into direct heat exchanging relation with the asphaltic stock containing the high boiling wax bearing fraction without prior heating of said asphaltic stock to a temperature at which substantial decomposition occurs, maintaining in said receptacle a maximum temperature approximating 820° F.-840° F. and maintaining therein a liquid body equivalent in volume to about 8-10 minutes discharge of residual stock mixture therefrom, whereby the viscosity of the residual components of the asphaltic stock introduced into said receptacle is reduced, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, and condensing this high boiling wax bearing fraction and supplying it to said heating.

8. In the manufacture of gasoline and fuel oil from asphaltic petroleum stocks containing a high boiling wax bearing fraction of the type generally occurring in California, the improvement which comprises heating a stream of distillate oil to a high cracking temperature under super-atmospheric pressure and controlling the temperature, temperature gradient, pressure and time during said heating to prevent substantial formation of carbon therein, reducing the pressure on the hot oil products of said heating and introducing them into an externally unheated vapor separating receptacle and therein bringing said hot oil products into direct heat exchanging relation with the asphaltic stock containing the high boiling wax bearing fraction without prior heating of said asphaltic stock to a temperature at which substantial decomposition occurs, maintaining a temperature and a pressure in said vapor separating receptacle sufficient to effect a reduction of the viscosity of residual components of said asphaltic stock but without substantial formation of carbon therein, taking off from said receptacle a residual stock mixture including the high boiling wax bearing fraction and a vapor mixture including gas oil and gasoline, vaporizing the high boiling wax bearing fraction from this residual stock mixture without substantial decomposition by the contained heat of the oil in an evaporator maintained under a pressure lower than that maintained in said receptacle, and condensing this high boiling wax bearing fraction and supplying it to said heating.
